UNITED STATES PATENT OFFICE.

SAMUEL G. GOSS, OF GLENCOE, ILLINOIS, AND RALPH C. SEYMOUR, OF LARCHMONT, NEW YORK.

MACHINE FOR OPERATING UPON WEBS.

1,159,017.

Specification of Letters Patent. Patented Nov. 2, 1915.

Application filed November 25, 1913. Serial No. 802,989.

To all whom it may concern:

Be it known that we, SAMUEL G. Goss and RALPH C. SEYMOUR, citizens of the United States, residing, respectively, at Glencoe, in the county of Cook and State of Illinois, and at Larchmont, in the county of Westchester and State of New York, have jointly invented new and useful Improvements in Machines for Operating upon Webs, of which 10 the following is a specification.

The invention relates to machines for operating upon a web of paper or like material, and more especially to machines for cutting and also, if desired, for collecting, a web, 15 such as a printed web, run from a printing press or like machine.

The objects of the invention are in part set forth hereinafter, and in part will be obvious herefrom, and are attained or effected 20 by the means and instrumentalities pointed out in the accompanying claims.

The invention consists in the novel parts, arrangements, improvements and combinations herein shown and described.

25 The accompanying drawings, referred to herein and forming a part hereof, illustrate one embodiment of the invention, the same serving in connection with the description herein to explain the principles of the invention.

30 Of the drawings: Figure 1 is a side elevation of a machine constructed in accordance with the principles of the invention, with the front frame removed for the sake of clearness; Fig. 2 is a side elevation of such machine looking at Fig. 1 from the right; Fig. 3 is a detail in elevation, on an enlarged scale, of one member of the compensating device; Fig. 4 is a view similar to Fig. 3 of 40 the other or coöperating compensating device; Fig. 5 is a detail elevation, on a different enlarged scale, of one of the cutters or shearing blades; and Fig. 6 is a partly diagrammatic view illustrating the taking 45 up of the web in order to make the cut straight across the web.

Referring to the accompanying drawings, illustrating by way of example one embodiment of the invention, a web α is supplied 50 from a suitable source, such as a printing press or like machine. Any suitable form of web forwarding devices may be provided, and as embodied herein, such devices comprise a series of tapes 1 coöperating with 55 one surface of the web and a corresponding

series of tapes 2 (shown fragmentarily in the drawings) acting upon the opposite face of the web. The tapes 1 pass over a series of rollers 3, carried upon a shaft 4, and also over a series of rollers 5, carried upon a 60 shaft 6. The series of tapes 1 likewise pass over a series of tension rollers 7. Rollers 7 are mounted in a suitable manner, as upon arms 8, carried upon a shaft or other support 9, and placed under tension in a suitable manner, as by springs or otherwise. The tapes 2 are shown passing over a corresponding series of rollers 10, carried upon a suitable shaft 11, and are provided with other rollers and tension devices, not shown. Certain of the tape rollers will be driven to give the tapes their required motion, in a well known manner.

The web is forwarded directly or indirectly to suitable cutting devices, and in 75 accordance with certain features of the invention said devices are constructed and arranged to cut the web transversely but in a slightly diagonal direction referred to the run of the web, thereby securing a shearing 80 action and a clean cut of the web while it is on the run; the invention providing in connection with the foregoing means and in coöperation therewith compensating devices which cause the actual cut to be made 85 straight across the web, instead of diagonally. In accordance with certain features of the invention, such compensating means or device acts to take up the web at one side and gradually across in a diminishing 90 degree so as to just compensate for the diagonal set of the cutting or shearing blades. Thus the speed of the web is maintained, a clean, certain and rapid cut is effected, and the edges of the sheet are kept true, or per- 95 pendicular to the sides and the necessity of a further trimming of such cut edges is obviated, as would otherwise be necessary in securing a first class product.

Referring in more detail to the embodied 100 form, the cutting means comprises a pair of rotary devices 15 and 16. The device 15 has a shaft 17 upon which are mounted a series of disks 18 rotating therewith and fixed thereto in any suitable manner as by collars 105 19. Formed along the disks 18 is a supporting web or bar 20, suitably recessed to receive the cutting or shearing blade 21, which blade may be secured in its support in any suitable manner, as by set screws or clamp- 110

ing bolts 22. The other or coöperating cutting or shearing device may be constructed in the same manner, and is shown provided with disks 24 carried upon a shaft 25. Said disks are connected by the web or bar 26, which carry the blade 27. The blades 21 and 27 are arranged slightly diagonally to the axes of rotation of the disks on which they are carried, as will be best seen from Fig. 5 of the drawing, said blades thus making a clean and positive cut in the running web.

Referring now more particularly to the embodied form of compensating device, a roller or like member 30 is provided on one side of the web, said roller being carried by a suitable shaft 31. In said roller 30 is formed a groove or recess 32 extending longitudinally of the roller, and preferably from one end to the other thereof. Said groove 32 is of greatest depth or extent, considered transversely of the roller 30, at one end of said roller and diminishing to nothing at the other end thereof. On the opposite side of the web α is a coöperating roller or cylinder 33 carried upon a shaft 34. The roller 33 is provided with a projection 35 arranged longitudinally thereof and shaped, proportioned and positioned to enter into the recess 32 periodically as the rollers 30 and 33 rotate. The groove 32 and projection 35 are also proportioned so as to lift or hold back the web just sufficiently to compensate for the diagonal set of the shearing blades 21 and 27, thus causing the gradual shearing cut which is made as the web runs through the cutting device to actually be a cut which is true or straight across the web and perpendicular to the sides thereof. It will be understood that there is thus realized the combined advantages of running the web rapidly through the machine, effecting the shearing or clean cut of the running web, and at the same time getting true edges on the product without resorting to an additional trimming.

In Fig. 6 of the drawings, which is of a diagrammatic nature, the two views may be regarded as looking at the parts from one end and then from the other. Taken together these views illustrate how the web is taken up at one side and in gradually decreasing degree across the web to nothing at the other side, as already explained.

Means are provided for directing the sheet forward from the cutting devices, and in the drawings a series of throat bars 40 are shown mounted upon a suitable rod 41 and a corresponding series of throat bars 42 mounted upon a rod 43, the sheets being guided downwardly through the throat or passageway formed between the opposed set of bars 40 and 42.

Receiving the forwarded sheets is a collecting cylinder 44, mounted upon a shaft

45, and provided with sets of grippers 46, 47 and 48 and adapted to receive the sheets in a well known manner. Suitable devices for receiving the bundles of associated sheets from the collecting cylinder 44 are provided such as a series of tapes 49 working over a series of rollers 50, and a series of coöperating tapes 51 working over a series of rollers 52. A suitable stripper 53 may also be provided.

It will be understood that the illustrated embodiment realizes the objects of invention and advantages specified, together with other objects and advantages. It will be further understood that variations and departures may be made from the illustrated machine without departing from the principles of the invention and without sacrificing its chief objects and advantages.

What we do claim as our invention and desire to secure by Letters Patent, is:

1. A web cutting machine including in combination web forwarding means, a pair of rotary web cutting devices comprising coöperating shearing blades arranged diagonally to their axes of rotation, and a compensating device acting on the web to cause the diagonal cutters to cut straight across the web.

2. A web cutting machine including in combination web forwarding means, a pair of rotary web cutting devices comprising coöperating shearing blades arranged diagonally to their axes of rotation, and a compensating device acting on the web prior to its entering the cutting device, to cause the diagonal cutters to cut straight across the web.

3. A web cutting machine including in combination web forwarding means, a pair of rotary cutting devices comprising coöperating shearing blades arranged diagonally to their axes of rotation, and a rotary compensating device acting on the web to cause the diagonal cutters to cut straight across the web.

4. A web cutting machine including in combination web forwarding means, a pair of rotary cutting devices comprising coöperating shearing blades arranged diagonally to their axes of rotation, and a rotary compensating device acting on the web prior to its entering the cutting device to cause the diagonal cutters to cut straight across the web.

5. A web cutting machine including in combination web forwarding means, a pair of rotary cutting devices comprising coöperating shearing blades arranged diagonally to their axes of rotation, and a rotary compensating device comprising coöperating members on opposite sides of the web and acting on the web prior to its entering the cutting device to cause the diagonal cutters to cut straight across the web.

6. A web cutting machine including in combination web forwarding means, web cutting means normally cutting diagonally to the web, and a compensating device for taking up the web gradually transversely thereof to cause the cutting means to cut straight across the web. 5
7. A web cutting machine including in combination web forwarding means, web cutting means normally cutting diagonally to the web, and a traveling compensating device for taking up the web gradually transversely thereof to cause the cutting means to cut straight across the web. 10
8. A web cutting machine including in combination web forwarding means, web cutting means normally cutting diagonally to the web, and a compensating device for taking up the web at one side to cause the cutting means to cut straight across the web. 15
9. A web cutting machine including in combination web forwarding means, web cutting means normally cutting diagonally to the web, and a traveling compensating device for taking up the web at one side to cause the cutting means to cut straight across the web. 20
10. A web cutting machine including in combination web forwarding means, a pair of traveling web cutting devices comprising co-operating shearing blades arranged diagonally to their mounting, and a compensating device acting on the web to cause the diagonal cutters to cut straight across the web. 25
11. A web cutting machine including in combination web forwarding means, a pair of traveling cutting devices comprising co-operating shearing blades arranged diagonally to their mounting, and a traveling compensating device acting on the web to cause the diagonal cutters to cut straight across the web. 30
12. A web cutting machine including in combination web forwarding means, a pair of traveling cutting devices comprising co-operating shearing blades arranged diagonally to their axis of rotation, and a traveling compensating device comprising co-operating members on opposite sides of the web and acting on the web prior to its entering the cutting device to cause the diagonal cutters to cut straight across the web. 35
13. A web cutting machine including in combination web forwarding means, traveling web cutting means normally cutting diagonally to the web, and a compensating device for taking up the web gradually transversely thereof to cause the cutting means to cut straight across the web. 40
14. A web cutting machine including in combination web forwarding means, traveling web cutting means normally cutting diagonally of the web, and a traveling compensating device for taking up the web 45
- gradually transversely thereof to cause the cutting means to cut straight across the web. 50
15. A web cutting machine including in combination web forwarding means, traveling web cutting means normally cutting diagonally to the web, and a compensating device for taking up the web at one side to cause the cutting means to cut straight across the web. 70
16. A web cutting machine including in combination web forwarding means, traveling web cutting means normally cutting diagonally to the web, and a traveling compensating device for taking up the web at one side to cause the cutting means to cut straight across the web. 75
17. A web cutting and sheet collecting machine including in combination web forwarding means, a pair of rotary web cutting devices comprising co-operating shearing blades arranged diagonally to their axes of rotation, and a compensating device acting on the web to cause the diagonal cutters to cut straight across the web, and a collecting device for collecting the sheets. 80
18. A web cutting machine including in combination web forwarding means, a pair of rotary cutting devices comprising co-operating shearing blades arranged diagonally to their axes of rotation, and a rotary compensating device acting on the web to cause the diagonal cutters to cut straight across the web, and a collecting device for collecting the sheets. 85
19. A web cutting machine including in combination web forwarding means, web cutting means normally cutting diagonally to the web, and a compensating device for taking up the web gradually transversely thereof to cause the cutting means to cut straight across the web, and a collecting device for collecting the sheets. 90
20. A web cutting machine including in combination web forwarding means, web cutting means normally cutting diagonally to the web, and a compensating device for taking up the web at one side to cause the cutting means to cut straight across the web, and a collecting device for collecting the sheets. 95
21. A web cutting machine including in combination web forwarding means, a pair of traveling cutting devices comprising co-operating shearing blades arranged diagonally to their axes of rotation, and a traveling compensating device acting on the web to cause the diagonal cutters to cut straight across the web, and a collecting device for collecting the sheets. 100
22. A web cutting and sheet collecting machine including in combination web forwarding means, traveling web cutting means normally cutting diagonally to the web, and a traveling compensating device for taking up the web at one side to cause the cutting 105
- 110
- 115
- 120
- 125
- 130

- means to cut straight across the web, and a collecting device for collecting the sheets.
23. A web cutting and sheet collecting machine including in combination web forwarding means, a pair of rotary cutting devices comprising coöperating shearing blades arranged diagonally to the axes of said rotary devices, a collecting cylinder having its axis substantially parallel to those of said rotary devices, and a compensating device acting on the web to cause said cutters to cut straight across the web.
24. A web cutting and sheet collecting machine including in combination web forwarding means, a pair of rotary cutting devices comprising coöperating shearing blades arranged diagonally to the axes of said rotary devices, a collecting cylinder having its axis substantially parallel to those of said rotary devices, and a compensating device taking up the web at one side to cause said cutters to cut straight across the web.
25. A web cutting and sheet collecting machine including in combination web forwarding means, a pair of rotary cutting devices comprising coöperating shearing blades arranged diagonally to the axes of said rotary devices, a collecting cylinder having its axis substantially parallel to those of said rotary devices, and a traveling compensating device taking up the running web at one side to cause said cutters to cut straight across the web.
26. A web cutting machine including in combination web forwarding means, a pair of rotary web cutting devices comprising co-
- operating shearing blades arranged diagonally to their axes of rotation, and a compensating device engaging the web to cause the diagonal cutters to cut straight across the web.
27. A web cutting machine including in combination web forwarding means, a pair of rotary cutting devices comprising coöperating shearing blades arranged diagonally to their axis of rotation, and a compensating device comprising coöperating members on opposite sides of the web and acting on the web prior to its entering the cutting device to cause the diagonal cutters to cut straight across the web.
28. A web cutting machine including in combination web forwarding means, a pair of rotary cutting devices comprising coöperating shearing blades arranged diagonally to their axis of rotation, and a compensating device comprising coöperating members on opposite sides of the web and engaging the web prior to its entering the cutting device to cause the diagonal cutters to cut straight across the web.

In testimony whereof, we have signed our names to this specification in the presence of two subscribing witnesses.
